ATTORNEY

UNITED STATES PATENT OFFICE.

ANDREW M. HUNT, OF NEW YORK, N. Y., ASSIGNOR TO STANDARD STOKER COMPANY,
INCORPORATED, A CORPORATION OF DELAWARE.

STOKER.

Application filed January 27, 1925. Serial No. 5,026.

This invention relates to mechanical stokers and particularly to such as embody means for raising coal to a point in the fire box above the fire through a suitable conduit and then distributing the same by means of jets of steam or other fluid over the fire. In stokers of this character, it is often desirable to have the jet structure extend into or encroach upon the delivery mouth 10 of the conduit. The jet structure which obstructs the mouth of the conduit, necessitates a lateral movement of the coal to get by the jet structure, and if this conduit is of approximately uniform section throughout 15 its length, the coal as it is moved laterally by the reaction from the jet structure will be crowded or packed against the walls of the conduit. This requires the application of excessive power to force the coal out and the 20 crowding may become so serious as to prevent the movement of the coal entirely.

One object of the present invention is to provide a conduit whose unobstructed area at the mouth is at least equal to its area at 25 that point beneath the mouth where the lateral reaction of the jet structure begins to be felt. In the form of invention herein illustrated, I accomplish this by gradually enlarging the total cross-section area of the 30 conduit at its upper end so that the increase of area at the top end of the conduit is not less than the area masked in a horizontal plane by the jet structure. In this manner, the packing of the coal is eliminated. In 35 order to provide an easy passage of the coal around the jet structure, I form this structure with a downwardly tapered bottom so as to guide the coal laterally in its upward movement.

40 Other objects and advantages will appear from the following description taken in connection with the accompanying drawing, wherein Fig. 1 is a side view of a locomotive stoker, partly in section, showing one embodiment of my invention.

Fig. 2 is a plan view of a portion of the structure shown in Fig. 1.

Fig. 3 is a detailed plan view of the rising conduit and the jet distributor head.

50 Fig. 4 is a rear elevation of the structure shown in Fig. 3.

Referring to Fig. 1, the numeral 10 indicates the rear water leg of a conventional locomotive boiler provided with a feed door

opening 11 which is located above the cab 55 deck 12.

Coal is fed to the fire box through a conveyor tube 14 in which is located the conveyor screw 15. The tube 14 terminates in an upwardly curving elbow 16 which merges 60 into the rising conduit 17. In the construction shown, the conveyor screw 15 does not extend beyond the elbow 16. The upwardly extending conduit 17 terminates in a mouth 19 above the level of the fire in the fire box. 65 Surrounding the upper portion of the conduit 17 is a protecting grate 18 which serves to maintain the fire away from the conduit 17. Secured at the upper end of the conduit 17 and extending within the mouth 19 is 70 a distributor head 20 which is provided with jet forming openings 21 adapted to direct jets of steam over the mouth 19 of the conduit 17 which blow the coal as it rises through the conduit over the protecting 75 grate 18 and distribute the same on the fire. Steam to supply the jets is supplied through the piping 22, which in the construction illustrated, extends downwardly between the conduit 17 and the water leg 10, thence 80 under the mud ring 23 of the locomotive boiler and upwardly to the valves 24, of which one only is shown, and manifold 25.

In operation of the structure thus far described, the coal which is advanced -from 85 the locomotive tender by the screw 15, upon leaving the end of the screw, becomes consolidated into a symmetrical stream or core in the elbow 16 and advances around the easy upward curve thereof and through the 90 unobstructed conduit 17 to the mouth 19 where it comes into the path of the steam jets which issue from the openings 21 in the distributor head 20. These jets serve to 95 carry and distribute the coal over the fire.

It will be seen that the distributor head 20 occupies a portion of the mouth 19 and so would normally tend to interfere with the free movement of the coal out of the conduit 17. In order to prevent this, the conduit 17 is gradually enlarged at its upper end from 100 the point 28 so as to form squared corners 29 at the mouth 19. In practice, the conduit 17 is constructed so that its unobstructed cross-sectional area gradually enlarges from 105 the bottom to the mouth 19. In order to provide an easy passage for the coal around the distributor head 20, I preferably form

the bottom of the head with a downward wedge as shown in dotted lines at 26 in Fig. 4.

I claim:

5. 1. The combination of a fire box, a stoker, comprising an upwardly curved conduit terminating in a delivery opening in the fire box, means for supplying coal to said conduit, and a distributor head having a downwardly tapered bottom, positioned at the top of said conduit and having jet forming means in line with the delivery opening of said conduit to distribute the coal therefrom, said conduit having throughout its length an expanding unobstructed cross-sectional area so that it flares toward its outlet.
10. 2. The combination of a fire box, a stoker comprising an upwardly curved conduit terminating in a substantially vertically directed delivery opening in the fire box above the level of the fire, means for supplying coal to said conduit and a separate distributor head positioned at the top and
15. at the rear wall of said conduit and having jet forming means in line with the delivery opening of said conduit to distribute coal therefrom, said conduit having throughout its length an expanding unobstructed cross
20. sectional area so that it flares toward its outlet, and also having at its delivery opening an offset section for attaching said distributor head to said conduit.
25. 3. The combination of a fire box, a stoker comprising an upwardly curved conduit terminating in a substantially vertically directed delivery opening in the fire box above the level of the fire, means for supplying

coal to said conduit and a separate distributor head attached to the rear wall of said conduit having jet forming means at the rear of said conduit, the jets therefrom being adapted to sweep across the entire delivery opening of said conduit to distribute the coal, said distributor head extending into said delivery opening and formed with a downwardly tapered bottom to prevent clogging of the coal at the distributor head, said conduit having throughout its length an expanding unobstructed cross sectional area so that it flares toward the delivery opening.

4. In a locomotive stoker the combination of a fire box, an upwardly extending curved conduit terminating in a substantially vertically directed delivery opening in the fire box above the level of the fire, means for supplying coal to said conduit, a detachable distributor head positioned at the top of said conduit and having jet forming means in line with the delivery opening of said conduit to distribute the coal therefrom, said conduit being of substantially circular cross section throughout its lower portion and being expanded to form substantially square corners adjacent the distributor head and an arcuate formation diametrically opposite said square corners whereby the unobstructed cross sectional area of the conduit throughout is slightly expanding in the longitudinal direction of the fire box so that the conduit flares toward its delivery opening, said conduit having its rear wall offset for attaching said distributor head thereto.

ANDREW M. HUNT.
